UNITED STATES PATENT OFFICE.

HARRY F. NILES, OF CHICAGO, ILLINOIS, ASSIGNOR OF ONE-THIRD TO EVA A. SCHLICK, OF COOK COUNTY, ILLINOIS.

VALVE.

1,338,838.

Specification of Letters Patent.

Patented May 4, 1920.

Application filed June 12, 1919. Serial No. 303,743.

To all whom it may concern:

Be it known that I, HARRY F. NILES, a citizen of the United States, residing at Chicago, in the county of Cook and State of Illinois, have invented certain new and useful Improvements in Valves, of which the following is a specification.

My invention relates to improvements in valves.

10 One of the objects of the invention is to provide a puppet valve that will permit some lateral displacement of its stem without disturbing its seating relation with its associated port.

15 Another object is to improve the structure disclosed in my Letters Patent of the United States No. 1,282,918 granted to me October 29, 1918.

Other, further and more specific objects 20 of my invention will become readily apparent to persons skilled in the art, from a consideration of the following description when taken in conjunction with the drawings, wherein—

25 Figure 1 is a central vertical section of a valve showing a part of an engine structure containing a conduit and a valve port.

Fig. 2 is a section taken on line 2—2 of Fig. 1.

30 In both views the same reference characters are employed to indicate similar parts.

Valves of the puppet type consist, generally, of a disk having an angularly disposed rim affording a seating surface, in coöperation 35 with a similar surface surrounding a port adapted to be closed and opened by the valve.

Such valves are provided with a centrally positioned stem, perpendicular to the face 40 of the disk, and this stem is guided rigidly by means that permits free vertical movement of the valve but which holds the valve, otherwise, in rigid relation with its port.

Any lateral displacement of the stem, due to 45 wear of the stem or its guide, permits the valve to cock up on one edge or the other of its seat, leaving relatively large free surfaces of the seat exposed upon which carbon is deposited, thereafter preventing effective 50 closing of the port and causing loss of compression in the cylinders of the engine.

In my former patent the valve was made in the form of a globe or a segment of a globe and from the same radial point, or 55 globe axis, a globular guide surface was de-

scribed, upon which was seated and around which was movable the guide for the valve stem.

I have found, from practice, that while such an arrangement is practical and operative when new, that any unequal wear of the guide or the valve will disturb their mutual coöperation to some extent and such an arrangement does not contribute, to as large an extent, toward bringing the valve 65 stem back to its former vertical position when it has been once laterally displaced. I therefore provide a flat surface 60 below the valve which has a tendency of itself to bring the valve back into its normal position and 70 which is arranged to coöperate with the valve at all times independently of any relative wearing away of the parts.

In the disclosure of my invention, as exemplified by the drawings, I have shown a 75 conventional structure in which 5 is a frame containing a conduit or gas passage 6 and closed by walls 7—7. In the wall 7 is a valve port 8 having a valve seating surface 80 curved to conform with the seating surface of the valve. The valve 9 has a seating surface 10 conforming in outline with that of a globe, the axis of which would be at the same point as that from which the port seating surface was described, or in other words, 85 the curve of the valve seat and the port seat are struck from the same axial point and of substantially equal radius.

The valve stem 13, of the valve, is not rigidly guided and permitted to move only 90 in a vertical plane, as in usual practice. The stem is surrounded by a sleeve 14 having a laterally extending head 15, which bears against the under side of the sliding plate 11 through which the valve stem passes and 95 which is laterally movable upon the flat surface 11' with which the plate is in contact, and which is the lower surface of the wall 17.

Now it is evident that when the lower end 100 of the valve stem is moved laterally, to a slight extent, that the valve 9 will not leave its seat, although there may be change of contacting surfaces. While this movement may occur the plate 11 will be moved laterally on its confronting flat surface without 105 being moved axially and the spring 19, which seats the valve, will tend to move the plate back into its former position.

The open spiral spring 19 surrounds the valve stem 13 and bears against the head 15 110

on the sleeve 14. The head being immediately in contact with the plate 11 yieldingly holds the plate in contact with the lower surface 11 of the wall 17. The other end of 5 the spring bears against the washer 20 that affords an abutment therefor, and which is held in place on the stem by the pin 21. The spring yieldingly holds the valve closed in whatever position it may be, with reference 10 to its contacting surface with its underlying seat, and it also yieldingly holds the plate 11 in contact with the surface 11' and serves as a means for automatically bringing the stem back in a true vertical position when 15 it has been once deflected therefrom. The valve-moving stem 23 is arranged, axially, with the valve 13, and has its confronting end concaved, as at 24, to assist in bringing the two stems in true alinement when the 20 valve is being opened. This effect is augmented by the operation of the plate 11 upon its seat 11' in coöperation with the spring. A cam 24 on a shaft 25 tends to vertically move the valve to open position, which is 25 closed by the operation of the spring when the cam is moved substantially a half revolution.

Having described my invention, what I claim is—

30 1. A valve structure having in combinative association, a puppet valve with a stem, and a head provided with a globe-like seat-

ing surface; a wall, having a port with a coöperating surface, whereupon to seat the valve; another wall spaced away from the 35 port wall having an opening to permit some lateral movement of the valve stem and through which the valve stem passes and having a flat surrounding surface; a flat plate surrounding the valve stem and in contact with said flat wall, and a spring to close the valve and bearing on said plate to yieldingly hold it in contact with said surface.

2. A valve structure having in combinative association, a puppet valve with a stem, 45 and a head provided with a globe-like seating surface; a wall having a port with a co-operating surface, whereupon to seat the valve; another wall spaced apart from the port wall having an opening to permit some 50 lateral movement of the valve stem and through which the valve stem passes and having a flat surrounding surface; a flat plate surrounding the valve stem and in contact with said flat wall surface; a sleeve axially movable on said stem having a head closing the opening in said plate and a spring surrounding the stem to close the valve and to seat the head of the sleeve in the opening in the plate.

In testimony whereof I hereunto subscribe my name.

HARRY F. NILES.
